UNITED STATES PATENT OFFICE.

HERBERT HUNTINGDON DAVISON, OF WINNIPEG, MANITOBA, CANADA.

SHEAF-LOADER.

1,078,132.

Specification of Letters Patent.

Patented Nov. 11, 1913.

Application filed July 8, 1912. Serial No. 708,226.

To all whom it may concern:

Be it known that I, HERBERT HUNTINGDON DAVISON, of the city of Winnipeg, in the Province of Manitoba, Canada, have 5 invented certain new and useful Improvements in Sheaf-Loaders, of which the following is a specification.

My invention relates to a device for loading sheaves and the object of the invention 10 is to provide a machine embodying a driven adjustable elevator and a dump rack wherein the sheaves are picked up and elevated by the elevator or conveyer and deposited into the dump rack, the lower end of the 15 elevator being pivoted so that it can be adjusted to the various requirements of the ground, while the upper end is adjustably swung to allow the sheaves to be more or less evenly stacked in the dump rack.

20 A further object of the invention is to supply a machine having the elevator driven by the traction wheels which can be backed up without the elevator being operated.

25 With the above objects in view the invention consists essentially in a main frame supported forwardly on caster wheels and rearwardly on tractor wheels, a dump rack mounted on the frame to the rear, an inclined elevator or conveyer carried by the frame and having the upper and lower ends thereof adjustable, and means for driving the elevator, the parts being arranged and constructed as hereinafter more particularly described.

Figure 1 is a side view of the machine. Fig. 2 is a front view thereof. Fig. 3 is an enlarged detailed longitudinal sectional view through the elevator and adjoining 40 parts. Fig. 4 is an enlarged detailed sectional view through the machine, the section being taken in the plane denoted by the line X X', Fig. 2. Fig. 5 is an enlarged detailed sectional view through the machine, the section being taken in the plane denoted by the line Y Y', Fig. 2. Fig. 6 is an enlarged detailed front elevation of the clutch member of the back axle. Fig. 7 is an enlarged detailed end elevation of the 45 inner clutch member, the wheel and outer clutch member being removed from the axle.

In the drawings like characters of reference indicate corresponding parts in each figure.

1 represents a substantially rectangular 55 main frame formed from side beams 2 and 3 and an end beam 4, which frame is carried rearwardly by an axle 5 on which I have mounted rotatable traction wheels 6, and is supported forwardly by two standards 7 and 8 supplied at the lower end with caster wheels 9.

10 is an arched or yoke-shaped rod spanning the forward or open end of the frame.

11 and 12 are two inclined angle iron 65 bars secured permanently at their lower ends to the beams 1 and 2 and at their upper ends to two uprights 13 secured to the main frame.

14 and 15 are a further pair of angle iron 70 bars hinged at 16 to the lower ends of the bars 11 and 12 and forming in reality a hinged or adjustable lower extension of such bars.

17 is a cross shaft rotatably mounted in 75 the lower ends of the bars 14 and 15 and having the ends extending there beyond and entering slots 18 formed in the standards 7 and 8, which slots it will be noticed are arched, the center point of the arch being at the hinge 16. The ends of the shaft are carried by upwardly directed rack bars 19 which engage with pinions 20 mounted on short spindles 21 extending from quadrants 22 permanently secured at 23 to the 80 main frame forwardly.

24 are rollers holding the rack bars against the pinions, and 25 are levers swung on the spindles 21 and secured to the pinions 20. The levers are each supplied with 90 the usual hand latch 26 and detent 27 which operate over the quadrant. It is to be noticed that the ends of the main frame and the inner faces of the standards 7 and 8 are cut away at 28 to allow the rack bars to 95 swing slightly sidewise to accommodate the slots.

29 is a cross shaft mounted in the upper end of the uprights 13 and passing through the angle bars 11 and 12.

30 and 31 are angle iron bars pivotally secured at 32 to the upper ends of the angle bars 11 and 12 and forming in reality an upper extension of these bars.

33 is a cross shaft mounted in the upper 105 ends of the bars 30 and 31, and 34, 35, and 36 are sheet metal plates secured to the in-turned flanges of the angle iron bars 11 and

12, 14 and 15, 30 and 31, respectively, these parts forming what I desire to call my adjustable conveyer or elevator frame.

37 and 38 are a pair of chain wheels located on the shaft 17, and 39 and 40 are a further pair of chain wheels fixed on the shaft 33, which pairs of wheels are connected by endless chains 41 and 42, supplied with suitably spaced connecting cross slats 43. Each cross slat is supplied with a set of prongs 44. A tube 45 is inserted on the shaft 17 between the chain wheels 37 and 38, which tube serves to reinforce the cross slats as they pass around the lower end of the conveyer.

46 and 47 are adjusting arms secured permanently to the sides of the angle bars 30 and 31 and having their free ends connected by cables 48 to a winding shaft 49 carried by the angle bars 11 and 12.

50 is a crank fixed on the end of the shaft for turning the same, and 51 is a ratchet wheel on the shaft adjoining the outer face of the bar 11.

52 is a pivoted ratchet engaging with the ratchet wheel. The arms can be drawn up or released as will readily be seen by turning the crank so that the upper end of the conveyer or elevator can be raised or lowered as desired.

In order to take up any slack in the chains which may appear when the upper end of the conveyer is adjusted I have placed two rocking bars 53 of channel iron cross section on the shaft 29, which bars are fitted with loose rollers 54 at their ends. These rollers carry the chains on the ascending side of the conveyer at all times.

55 is a dump rack pivotally secured to the rear end of the main frame at 57.

58 is a spring catch secured to the dump rack and engageable with a cross bar 59 carried by a cross beam 60 in turn supported by the beams 2 and 3. The catch holds the rack against dumping until released by the movement of a lever 61 connected to the catch by a link 62, which lever is under the control of the operator. The dump rack is positioned so as to receive material deposited from the upper end of the conveyer, and the upper end of the conveyer is arranged as already described so that it can be raised or lowered to spread the sheaves evenly in the rack.

63 is a counter shaft rotatably mounted in the main frame, and 64 is a chain wheel keyed on the shaft and connected through a chain 65 with a chain wheel 66 located on the end of the shaft 29.

67 is a second chain wheel on the shaft 29 and it is connected through a chain 68 with a chain wheel 69 on the end of the shaft 33.

The axle 5 is carried by bearing blocks 5' secured to the rear end of the main frame and the bearing blocks are partially cored out at 5" to receive rotatably a female clutch member 70 feathered on the axle at 71 and acted upon by a spiral spring 72 housed within the boxing and encircling the axle. The traction wheels are each provided with male clutch members 73 which rotate with them and engage continuously with the female members.

74 is a chain wheel fixed centrally on the axle and connected through a chain 75 with a chain wheel 76 fixed on the shaft 63. According to this construction it will be seen that as long as the machine advances the traction wheels will rotate the axle 5 and drive the conveyer, but immediately the machine is backed up the traction wheels will turn free of the axle as the male member of the clutch will escape over the female member, the female member springing into the boxing.

77 is a cross bar permanently secured to the frame forward of the traction wheels, which beam carries double trees 78 whereby draft animals can be attached to the machine.

79 is a further cross beam secured to the frame. This beam is supplied with the usual neck yokes 80.

What I claim as my invention is:

In a sheaf loader, the combination comprising a main frame having an open forward end, traction wheels supporting the main frame rearwardly, standards secured to the forward ends of the main frame and provided with arched slots, caster wheels supporting the standards, an inclined endless conveyer mounted on the frame and having pivoted upper and lower ends, the lower end of the conveyer being guided in the slots aforesaid, means for adjusting the upper end of the conveyer, means for adjusting the position of the lower end of the conveyer in the slots, means for driving the conveyer, and means for taking up any slack appearing therein when in the adjusted positions, as and for the purpose specified.

Signed at Winnipeg, this 20th day of December, 1911.

HERBERT HUNTINGDON DAVISON.

In the presence of—

G. S. ROXBURGH,
R. FOSTER.
